UNITED STATES PATENT OFFICE.

ANDREW L. WAGSTAFF, OF KANSAS CITY, MISSOURI, ASSIGNOR, BY MESNE ASSIGNMENTS, OF TWO-THIRDS TO AMERICAN BOTTLE CASE COMPANY, A CORPORATION OF MISSOURI.

KNOCKDOWN BOTTLE-CASE.

1,364,968.

Specification of Letters Patent. Patented Jan. 11, 1921.

Application filed January 21, 1919. Serial No. 272,240.

To all whom it may concern:

Be it known that I, ANDREW L. WAGSTAFF, a citizen of the United States, residing at Kansas City, in the county of Jackson and State of Missouri, have invented certain new and useful Improvements in Knockdown Bottle-Cases, of which the following is a specification.

My invention relates to cases for holding soda bottles, milk bottles, or in fact all kinds of bottles carried in cases, and one object is to provide a comparatively simple, inexpensive and compact device capable of standing the rough usage to which cases of this character are subjected.

A further object is to provide a nailless box of light but substantial construction in which the different parts can be readily taken apart for shipment in knockdown form to effect a saving in space and freight charges.

Another object is to provide a case embodying means whereby any looseness caused by shrinkage or otherwise can be readily taken up and thus prevent the case from collapsing from such cause.

Other objects will hereinafter appear, and in order that the invention may be fully understood, reference will now be made to the accompanying drawings, in which:

Fig. 1 is a plan view of the case set up ready for use.

Fig. 2 is a cross section on line II—II of Fig. 1.

Fig. 3 is a broken, longitudinal section on line III—III of Fig. 1.

Fig. 4 is a perspective view of the various parts disassembled.

Fig. 5 is a detail of a tie-rod, a number of which are employed in the construction of the case.

In carrying out the invention, I employ end members 1 and 3, side members 5 and 7, bottom members 9, and a partition 12. The number of partitions may be increased, or they may be dispensed with in accordance to the size of case desired.

The end members 1 and 3 are provided with vertical grooves 14 and 16 near their margins and horizontal grooves 18 and 20, respectively, adjacent to their bottom edges. Said end members 1 and 3 are also provided with openings 22 and 24, respectively, through which the hands may be inserted,

so that the case and its contents can be conveniently carried.

The side members 5 and 7 have beveled vertical edges 26 and 28 to fit snugly within the vertical grooves of the end members 1 and 3, respectively. Said side members 5 and 7 also have vertical grooves 30 and 32, respectively, about midway between their ends to receive the ends of the partition 12.

The bottom members 9 have beveled edges 34 and 36 to fit into the horizontal grooves 18 and 20 of the end members 1 and 3, respectively. When assembled the case is divided into two main compartments 38 and 40 by the partition 12, and said main compartments 28 are divided into minor compartments 42 and 44, respectively, by longitudinal tie-rods 46 and transverse tie-rods 48 which extend through holes drilled in the ends, sides, and the partition of the case. Each tie-rod is provided at one end with a conical head 50 and at its opposite threaded end with a nut 52, which latter like the former is countersunk in the walls of the crate, so that they cannot become damaged and will not interfere with a number of cases being packed closely side by side. The conical heads 50 are provided with transverse slots 54, so that the tie-rods may be rotated with a screw-driver to draw the ends and sides of the case firmly together, and so that any looseness caused by shrinkage or other causes can be readily taken up. When the tie-rods are thus rotated the nuts 52 are prevented from rotating by the openings in which they are countersunk.

The minor compartments 42 and 44 are of a size to receive the bottles to be carried in the case, said bottles being reliably held from tipping or shifting about by the tie-rods which are arranged in two tiers to provide four bearing surfaces near the bottom and four near the middle or upper portion of the bottles.

The lower edges 52 and 54 of the end members 1 and 3, respectively, project below the bottom members 9 and are slightly rounded to act as runners when the case and its contents are being slid over the upper edge of a vehicle body or other relatively smooth surface.

By joining the ends of the various members as above specified and drawing them firmly into engagement with the tie-rods,

nails are not required to hold the different parts together and hence the case can be readily taken apart for shipment or storage in a small space. The tie-rods are also 5 stronger, lighter and occupy less space than wooden partitions, and hence the case can be made smaller and narrower than if wooden partitions were employed, and a large saving in lumber is effected.

10 From the foregoing description, it is apparent that I have produced a case embodying the advantages above enumerated, and while I have shown and described the preferred form of the invention, I reserve the 15 right to make such changes in the construction, combination and arrangement of parts as properly fall within the spirit and scope of the claims.

Having thus described my invention, 20 what I claim and desire to secure by Letters Patent, is:

1. In a box, a bottom, sides and ends, rods extending between the ends and through the latter, rods extending between the sides and 25 through the latter, abutments on one end of each rod engaging the outer faces of the sides and ends respectively and nuts

threaded on the opposite ends of the rods and abutting the outer faces of sides and ends respectively whereby upon tightening 30 of the nuts the sides and ends can be drawn together.

2. In a box, a bottom, sides and ends, spaced upper and lower rods extending between the ends and through the latter, 35 spaced upper and lower rods extending between the sides and through the latter, abutments on one end of each rod engaging the outer faces of the sides and ends respectively and nuts threaded on the opposite ends of 40 the rods and abutting the outer faces of the sides and ends respectively whereby upon tightening of the nuts the sides and ends can be drawn together, the upper and lower rods between the ends and the upper and lower 45 rods between the sides intersecting to form bottle compartments.

In testimony whereof I affix my signature, in the presence of two witnesses.

ANDREW L. WAGSTAFF.
